UNITED STATES PATENT OFFICE.

FRANK AVERILL FOX, OF BROOKLYN, NEW YORK.

LINK FOR CROSS-CHAINS OF ANTI SKID DEVICES.

1,018,179.

Specification of Letters Patent.

Patented Feb. 20, 1912.

Application filed December 6, 1911. Serial No. 664,218.

To all whom it may concern:

Be it known that I, FRANK AVERILL FOX, a citizen of the United States, residing at Brooklyn, in the county of Kings, State of New York, have invented certain new and useful Improvements in Links for Cross-Chains of Antiskid Devices, of which the following is a description, reference being had to the accompanying drawings, forming a part hereof.

My invention relates to cross chains for antiskid devices for tires of automobiles and other vehicles, and relates particularly to the construction of the links of such cross chains and the tongues by means of which they are interlocked with the other parts of the chain, and the means of securing the ends of the bent-over tongues to the body portions of the links, and my invention has for its object to so construct the parts above referred to as to enable the ends of the tongues to be quickly secured in place and so firmly held that they cannot be pulled out in use, and at the same time the links may be made and the cross chains assembled at comparatively slight cost.

With these objects in view my invention consists in the construction and combination of elements hereinafter described and claimed.

Referring to the drawings Figure 1 is a bottom view of a side link embodying my invention; Fig. 2 is a side view of the same; Figs. 3 and 4 are cross sectional views on lines *a-a* and *b-b* respectively of Fig. 1; Fig. 5 is a plan view of a cross chain having side links of the construction shown in Figs. 1 to 4 inclusive; Fig. 6 is a bottom view of a center or master link having tongues; Fig. 7 is a side view of the same, and Fig. 8 is a bottom view of a cross chain having the center or master link shown in Figs. 6 and 7.

In the drawings 1, in Figs. 1 to 5 inclusive, is the body portion of a side link of a cross chain. From one end of the body portion extends a tongue 2, which is of substantially uniform width throughout. From the other end of the body portion 1 extends a tongue 3, which is narrower midway its ends than at its ends, its end portion 4 being of the same width as the tongue 2.

In the back or bottom face of the body portion 1 is formed a recess 5 extending

from end to end of the body portion in line with the tongues 2 and 3, and of a depth corresponding to the thickness of the end portions of these tongues. This recess being of uniform depth, that is, having its bottom parallel with and at a uniform distance throughout its length from the front face of the link, and being of uniform width throughout, is readily machined to the precise dimensions desired. Near their ends the tongues 2 and 3 are provided with oppositely formed recesses 6 near, but not at the ends of, the tongues, the ends 7 beyond these recesses being of the full width and thickness of the end portions of the tongue. At the sides of the recess 5 in the body portion of the link are formed lugs 8 arranged in pairs, and of such shape and size that when bent over they will each fit and fill one of the recesses 6 in an end portion of one of the tongues. When the lugs 8 are bent down into the recesses 6 they not only hold the end portions of the tongues against the bottom of the recess 5, but also, by reason of the ends 7 being of full width and thickness, interlock with the recesses, effectively holding the tongues against longitudinal strain. The tongues 2 and 3 are preferably of such length that their ends will abut when bent into the recess 5, and the lugs 8 when bent down into the recesses 6 completely fill them, so that the inner surface of the body portion of the link presents a smooth practically unbroken surface.

In Fig. 5 is shown a chain comprising side links of the construction shown in Figs. 1 to 4 inclusive, with a center or master link 10 having loops 11 through which the tongues 2 are passed before their ends are bent over into the recesses 5, these loops 11 being preferably formed integral with the body portion of the link.

In Fig. 6 is shown a center or master link embodying my invention, having both of its tongues 2 of substantially uniform width throughout their length, the body portion of the link having the recess 5 of uniform width throughout and arranged the same as in the form shown in Figs. 1, 2 and 3. The tongues have the recesses 6 and the solid end 7, and the body portion is provided with the lugs 8, which are adapted to be turned down into the recesses 6, as in the form shown in Figs. 1, 2 and 3. With the form of center link the side links are nec-

essarily provided at their ends contiguous to the center link with loops 12 to receive the tongues 2, as shown in Fig. 8.

Having thus described my invention, what I claim is:

- 5 1. A link for cross chains of antiskid devices comprising a body portion having a recess in its back or bottom face, a tongue extending from one end of the body portion having its end portion adapted to fit the recess in the body portion and having opposite recesses formed in its end portion near but not extending to its end, and oppositely arranged lugs on the body portion adapted to be turned down into and to fit the recesses in the end portion of the tongue.
- 10 2. A link for cross chains of antiskid devices comprising a body portion having a recess of uniform width throughout its length formed in its back or bottom face, a tongue extending from each end of the body portion, the tongues having their end portions adapted to fit the recess in the body portion and each having oppositely arranged recesses in its end portion but not extending to its end, and pairs of oppositely arranged lugs formed on the body portion adapted to be bent down into said recesses in the end portions of the tongues.
- 15 3. A link for cross chains of antiskid devices comprising a body portion having a recess of uniform width throughout its length formed in its back or bottom face, a tongue extending from each end of the body portion, the tongues having their end

portions adapted to fit the recess in the body portion, the tongues being of such length that their ends abut when bent into the recess in the body portion, the tongues having oppositely arranged recesses in their end portions not extending to their ends, and pairs of oppositely arranged lugs on the body portion adapted to be bent down into the recesses in the end portions of the tongues to lock them against strain.

4. A link for cross chains for antiskid devices comprising a body portion having a recess of uniform width throughout its length formed in its back or bottom face, a tongue extending from each end of the body portion, the tongues having their end portions adapted to fit and fill the recess in the body portion and each having oppositely arranged recesses in its end portion but not extending to its end, and pairs of oppositely arranged lugs on the body portion adapted to be bent down into and to fill the recesses in the end portions of the tongues, the parts being so proportioned that when the tongues are bent into the recess in the body portion and the lugs are bent into the recesses in the end portions of the tongues, the back or bottom face of the link presents a practically unbroken surface.

This specification signed and witnessed this fifth day of December, A. D. 1911.

FRANK AVERILL FOX.
